UNITED STATES PATENT OFFICE.

BJORGULO NORSTOG, OF WATFORD CITY, NORTH DAKOTA.

DIRIGIBLE HEADLIGHT.

1,239,034.

Specification of Letters Patent.

Patented Sept. 4, 1917.

Application filed February 28, 1917. Serial No. 151,518.

To all whom it may concern:

Be it known that I, BJORGULO NORSTOG, a citizen of the United States, residing at Watford City, in the county of McKenzie and State of North Dakota, have invented certain new and useful Improvements in Dirigible Headlights, of which the following is a specification, reference being had to the accompanying drawings.

10 This invention relates to certain improvements in dirigible headlights and has relation more particularly to a device of this general character especially designed and adapted for use in connection with vehicles of a motor-driven type; and it is an object of the invention to provide a device of this general character having novel and improved means whereby the headlight will be caused to move in unison with and in the 15 same general direction as the steering wheels.

It is also an object of the invention to provide a device of this general character having novel and improved means whereby the same may be supported in applied position.

20 The invention consists in the details of construction and in the combination and arrangement of the several parts of my improved headlight whereby certain important advantages are attained and the device is rendered simpler, less expensive and otherwise more convenient and advantageous for use, all as will be hereinafter more fully set forth.

The novel features of the invention will hereinafter be definitely claimed.

25 In order that my invention may be the better understood, I will now proceed to describe the same with reference to the accompanying drawings, wherein—

Figure 1 is an elevational view of a vehicle illustrating an embodiment of my invention applied thereto;

Fig. 2 is a fragmentary view in top plan of the forward end portion of the vehicle with my invention as herein embodied applied thereto and with certain of the parts indicated by dotted lines;

Fig. 3 is a view partly in elevation and partly in section of a dirigible headlight constructed in accordance with my invention as herein disclosed;

Fig. 4 is a view partly in section and partly in elevation of the upper portion of

the device as disclosed in Fig. 3 and at substantially right angles to the disclosure in Fig. 3;

55

Fig. 5 is a sectional view taken substantially on the line 5—5 of Fig. 4; and

Fig. 6 is a sectional view taken substantially on the line 6—6 of Fig. 3.

As disclosed in the accompanying drawings, A denotes the front axle of a motor-driven vehicle and which is of a conventional type. Coacting with the axle A are the clamping blocks 1 through which is removably disposed the shank 2, the outer end portion of said shank being provided with the perforate head 3 while the opposite end portion of the shank has removably disposed therethrough a pin 4 preferably coacting with the washer 5 surrounding said shank whereby it will be perceived that the blocks 1 will be effectively clamped upon the axle A yet capable of being readily and conveniently removed when the requirements of practice may so necessitate.

75

6 denotes a vertically disposed rod loosely directed through the perforate head 3 and capable of axial rotation, and the lower extremity of said rod 6 is provided with the extension 7 preferably at right angles to the rod 6. The outer end portion of the extension 7 is reduced, as indicated at 8, and seated within the horizontally disposed sleeve 9 provided with the depending shank 10 loosely directed through the head or block 11. The shank 10 has disposed therethrough a removable pin 12 whereby it will be perceived that the sleeve 9 is effectively held against accidental displacement although said sleeve can be readily removed when required.

90

The block or head 11 is adapted to be clamped to the steering rod R of any ordinary or preferred type, said clamping means, as indicated at 14, being of any preferred 95 character.

Surrounding the rod 6 is the annular member or sleeve 15 which is held against movement longitudinally of the rod 6 through the medium of the set or clamping screw 16. The annular member or sleeve 15 is adapted to rest upon the upper face of the perforate head 3 whereby a downward movement of the rod is limited. It will also be

self-evident that the annular member or sleeve 15 is capable of convenient adjustment longitudinally of the rod 16 to readily meet the requirements of practice.

- 5 The upper end portion of the rod 6 is reduced, as indicated at 17, and said reduced portion is angular in cross section and is adapted to be freely received within the bore 18 of the elongated sleeve 19, said 10 bore 18 being of substantially the same cross sectional configuration as the reduced portion 17 so that the sleeve 19 will be caused to rotate in unison with the rod 6. The sleeve 19 is freely positioned within the upper standing barrel 20, the lower end portion 15 of which is provided with the flange 21 to provide means whereby the same may be secured to a suitable support such as a mud guard or fender G of a motor-driven vehicle 20 and as indicated by dotted lines in Fig. 2.

The upper end portion of the sleeve 19 is enlarged, as indicated at 22, to afford a head resting upon the upper end of the barrel 20 whereby the sleeve 19 is maintained 25 in applied position. Surrounding the head 22 is the annular member 23 held in applied position upon said head 22 through the medium of the clamping screw 24. As is believed to be self-evident the annular member 23 may be readily adjusted either longitudinally or axially of the head 22, as the occasion may require.

The annular member 23 is provided with the arms 25 adapted to afford a support for 30 the lamp or headlight L, said lamp or headlight L being indicated by dotted lines in Fig. 1.

The periphery of the sleeve 19 at a predetermined point intermediate its length is 40 provided with the annular recess or groove 26 which is adapted to receive the pin 27 disposed through the sleeve 19 and partially intersecting the bore thereof. By this arrangement it will be at once self-evident 45 that the sleeve 19 is effectively held against longitudinal movement independently of the barrel 20.

As the steering rod R forms no particular part of my present invention and as the arrangement and operation thereof is believed 50 to be obvious, a detail description and illustration of said rod and as particularly relates to its operation has been omitted. This is also true of the axle A.

Surrounding the barrel 20 at a predetermined point intermediate its length is the 55 split clamp 31 provided with the forwardly directed shank 28 disposed through the truss rod 29 interposed between the guards or 60 fenders G, and coacting with the outer end portion of the shank 28 is the nut 30 whereby it will be at once self-evident that the truss 29 serves as an additional means to support the barrel 20 and to hold the same

against vibration. It is also to be noted 65 that the split of the clamp 31 is extended longitudinally of the shank 28.

From the foregoing description, it is thought to be obvious that a headlight constructed in accordance with my invention is 70 of an extremely simple and comparatively inexpensive nature and is particularly well adapted for use by reason of the convenience and facility with which it may be assembled, and it will also be obvious that my 75 invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. In combination with an axle of a vehicle, clamping members co-acting with said axle, a headed shank disposed through said clamping members, means carried by the shank and co-acting with the clamping 90 members for maintaining said members in operative engagement with the axle, a lamp supporting rod rotatably supported by the headed shank, and means for rotating said rod.

2. A device of the character described comprising a rod mounted for rotary movement, means for rotating said rod, a barrel supported independently of the rod, a sleeve rotatably mounted within the barrel and 100 provided with a bore angular in cross section, an end portion of the rod being snugly insertible within the bore of the sleeve but capable of longitudinal movement independently of the sleeve, lamp engaging means 105 carried by the sleeve, and co-acting means carried by the barrel and the sleeve for holding said barrel and sleeve against relative longitudinal movement.

3. A device of the character described 110 comprising a rod mounted for rotary movement, means for rotating said rod, a barrel supported independently of the rod, a sleeve rotatably mounted within the barrel and provided with a bore angular in cross section, an end portion of the rod being snugly insertible within the bore of the sleeve but capable of longitudinal movement independently of the sleeve, and lamp engaging 115 means carried by the sleeve.

4. A device of the character described comprising a rod mounted for rotary movement, means for rotating said rod, a barrel supported independently of the rod, a sleeve rotatably mounted within the barrel 120 and provided with a bore angular in cross section, an end portion of the rod being snugly insertible within the bore of the

sleeve but capable of longitudinal movement independently of the sleeve, lamp engaging means carried by the sleeve, and means engageable with the barrel intermediate the length thereof to afford an additional support for the barrel and to hold the same against vibration.

In testimony whereof I hereunto affix my signature in the presence of two witnesses.

BJORGULO NORSTOG.

Witnesses:
